PASTE SCOURING CLEANSER

Philip Benjamin Dalton, Franklin Square, N.Y., assignor to Colgate-Palmolive Company, Jersey City, N.J., a corporation of Delaware

No Drawing. Application December 29, 1953
Serial No. 401,040

1 Claim. (Cl. 252—115)

This invention relates to certain improvements in 15 scouring cleansers and particularly to a new variety of paste scouring cleanser differing from those now in common use and having as one of the basic ingredients a highly effective material that eliminates many of the undesirable characteristics of present day paste scouring cleansers and gives them several new advantages.

This application is a continuation-in-part of my co-pending application Serial No. 347,416, filed April 7, 1953, now abandoned.

There is a present need for paste type scouring cleansers in the market today because in certain operations such as the cleansing of hotel bathroom sinks, pullman car sinks and metal surfaces, etc., the use of a powder cleanser is often excluded regardless of its merit. To meet that need the present invention provides a new paste type scouring cleanser having a non-soap anionic synthetic detergent base which is superior in foaming, detergent and lime soap dispersion and/or rinsing properties to any paste type cleanser heretofore known.

One of the difficulties encountered in preparing a paste type cleanser is to obtain the proper physical form without losing the desirable properties of the detergent. More particularly, the water content and gelling properties must be adjusted so that upon packaging the product it will flow readily at elevated temperatures and set up firmly at room temperature. The technique usually employed in packaging paste soap cleansers involves pouring the product into a container at a temperature no higher than 110° F. so as to avoid shrinkage and other undesirable properties. This means that the product flows readily at 110° F. and sets up firmly at room temperature. In preparing a paste type cleanser using a non-soap anionic synthetic detergent base an additional difficulty is encountered which is not present when preparing a soap base type paste cleanser. A non-soap anionic synthetic detergent has no gelling properties. The difficulties encountered in obtaining the proper physical form of the paste cleanser are therefore two-fold; the first being the proper water content and the second the addition of a suitable gelling agent. Having once obtained the proper physical form for the paste cleanser, should the product not be smooth, that is, should it be stringy or short, an additional difficulty is encountered in finding an agent which will give the product satisfactory consistency and appearance.

Broadly, the invention is concerned with a paste cleanser having a non-soap anionic synthetic detergent base. More particularly, the invention is concerned with a paste cleanser composition comprising a cleansing powder having a non-soap anionic synthetic detergent base combined with a gelling agent, a lubricating agent, and water.

In making paste scouring cleanser, it has been customary to use soap; that is, alkali metal salts of soap-forming fatty acids, as a base material or at least as an essential ingredient. Bentonite, soda ash, water and/or other ingredients are usually compounded with the soap

to make the final soap paste scouring cleanser. However, one disadvantage of using soap is that it forms insoluble curds with calcium and magnesium both of which are commonly present in water. With such curd formation the effectiveness of the soap detergent is materially reduced. This does not occur when a non-soap anionic synthetic detergent is used as a base ingredient in a paste type scouring cleanser.

It is therefore an object of this invention to provide 10 a paste type scouring cleanser having as a base ingredient a non-soap anionic detergent which will afford lime soap protection in water up to 300 p.p.m. hardness, and which will be characterized by good foaming, detergent and rinsing properties.

Other objects and advantages of the present invention will become apparent upon consideration of the following detailed description:

According to the present invention, it has been discovered that when a dry cleansing powder comprising an 20 abrasive, a non-soap anionic synthetic detergent, and a water-soluble inorganic phosphate is combined with a gelling agent, a lubricant and water, a paste scouring cleanser results which exhibits excellent foaming, detergent, rinsing and lime soap dispersion properties. More 25 particularly, it has been discovered that when a cleansing powder comprising silex, a non-soap anionic synthetic detergent and an alkali metal tripolyphosphate is combined with high titer soap, glycerin, and water, a paste scouring cleanser results which is superior in foaming, detergent, rinsing and lime soap dispersion properties to the powder soap alone or any of the soap base paste 30 cleansers heretofore known.

In determining the proportions of each component of the paste cleanser which will produce the desired result 35 it was found that the proportion of silex in the paste cleanser should be maintained preferably between about 50 to 73%, that the total phosphate content should preferably be maintained within a range of about 4 to 10% and that the non-soap anionic synthetic detergent content should preferably be within the range of about 2 to 10%. The range of the powdered cleansing agent in the paste cleanser should be maintained within a range of about 65% to 85%.

It was found that the water content must be maintained 40 between about 15 to 30% of the composition in order to establish and maintain the proper physical characteristics thereof. This means that the product shall be flowable at higher temperatures and set up firmly at room temperature. It also means that the content of the gelling agent, which is essential since a non-soap anionic synthetic detergent has no gelling properties, may be reduced to a minimum. For a high water content such as of the order to 40 to 50%, more thickening or gelling agents would be needed, but this would be undesirable 45 since it would reduce the amount of the effective detergent.

It was found that a high titer soap was satisfactory as 50 a gelling agent. When used in low concentration it thickened or gelled the formation to the proper degree whether at room temperature or elevated temperatures.

In addition to soap, various agents were investigated such as alkali metal alginates especially sodium alginate (Keltex), tri-alkylolamine salts of alginic acid especially a tri-isopropanolamine salt of alginic acid (Kelluble), various grades of carboxymethyl cellulose (e.g., alkali metal salts, especially sodium), and a moss extract (Krimco). While most of these materials exhibited thickening properties, all of them except soap showed one important defect. That is, the change in viscosity with the change in temperature was not great enough in the concentration investigated. When a sufficient amount of, say, sodium alginate was used to produce a thick product at room

3

temperature, it was not pourable at slightly elevated temperatures.

Since the amount of soap used as a gelling agent should be kept to a minimum, only a high titer soap was used because this gives more gelling power at lower concentrations as compared to the lower titer soap. The titer of the soap, to obtain the proper physical characteristics, should preferably be maintained from about 25° to 60° C. and said high titer soap should be present within a range of about 0.6% to 2.5% in the composition. More particularly, 1% of a 57.6° C. titer soap gave the best results.

In making up a paste scouring cleanser comprising powder cleanser, high titer soap and water, it was found that although the use of a high titer soap gave a stable product which poured at elevated temperatures and gelled at room temperatures, the paste was somewhat stringy and short. A lubricant such as glycerin was therefore added to give the paste product a better consistency and appearance, it being added to the product in relatively small amounts. It was found that the addition of between approximately 1 to 3% lubricant gave a smooth product of good consistency and appearance.

To illustrate the general process of preparing a composition of this type, the water, glycerin and soap were mixed in a common type soap crutcher, heated to between 160° and 206° F., and the cleansing powder was added to the solution over a period of about 1 to 15 minutes. By this method a minimum of foaming and air bubbles was produced in the mixture. The water-soap-glycerin was brought almost to a boil before adding the powdered cleanser. By doing this no external heat was necessary during mixing. The mixture was stirred to a smooth paste, usually no longer than about 5 to 10 minutes being required although periods as high as 40 minutes were successfully tried, and poured into a container at a temperature from 128° to 182° F. It was further found that should the soap be prepared in situ, by which is meant adding caustic and a fatty acid to the mixture rather than the preformed soap itself, the product was superior to the product obtained by adding preformed soap directly to the mixer.

Although the process is preferably performed by adding a powdered cleanser to the mixture of glycerin, soap and water, it is within the purview of this invention to add the components of the powdered cleanser individually to the mixture of the glycerin, soap and water. It was found that an equally satisfactory paste cleanser was obtained when the non-soap anionic synthetic detergent, silex and alkali metal tripolyphosphate such as sodium tripolyphosphate were added to the mixture of glycerin, soap and water.

Having described the present invention in its broader aspects, more detailed examples of the procedure and composition in accordance therewith are now given in order to assist in a better understanding of its various ramifications, it being understood that this is included herein for purpose of illustration rather than limitation. Percentages are by weight throughout the specification and claims unless otherwise indicated.

In Examples 1 to 6 the "cleansing powder" consists essentially of 87.2% silex, 6.2% commercial dodecyl benzene sulfonate and 6.2% sodium tripolyphosphate. In Example 7 the cleansing powder is as therein indicated.

EXAMPLE 1

	Percent
Cleansing powder	70.78
Water	27.20
Glycerin	1.01
Soap	1.01

In the preparation of this composition $\frac{1}{2}$ pound of glycerin, $\frac{1}{2}$ pound of soap, and 14 pounds of water were added to an Abbey mixer. This mixture was then heated

4

to 173° F. whereupon there was added to it over a period of 1½ minutes while being agitated 35 pounds of cleansing powder. The addition of the powder resulted in a lowering of the bath temperature to 150° F. The overall composition was mixed for a period of five minutes and then poured into a container at 144° F. A resulting analysis of the paste showed a specific gravity of 1.42 and a moisture content of 27.2%.

EXAMPLE 2

	Percent
Cleansing powder	75.05
Water	22.80
Glycerin	1.075
Soap (formed in situ)	1.075

In the preparation of this composition $\frac{1}{2}$ pound of glycerin, 14 pounds of water, and the calculated amount of hydrogenated tallow fatty acid composition consisting of 3.0% myristic, 28% palmitic, 63% stearic and 6.0% oleic acids and sodium hydroxide to make $\frac{1}{2}$ pound of soap were added to an Abbey mixer. This mixture was then heated to 168° F. whereupon there was added to it over a period of 1½ minutes while being agitated 35 pounds of the powdered cleanser. The addition of the powder resulted in a lowering of the bath temperature to 152° F. The over-all composition was then mixed for a period of five minutes and then poured into a container at 138° F. A resultant analysis of the paste showed a specific gravity of 1.38 and a moisture content of 22.8%.

EXAMPLE 3

	Percent
Cleansing powder	78.03
Water	19.80
Glycerin	1.085
Soap (formed in situ)	1.085

In the preparation of this composition 3 pounds of glycerin, 78 pounds of water and the calculated amount of hydrogenated tallow fatty acid composition consisting of 3.0% myristic, 28% palmitic, 63% stearic and 6.0% oleic acids and sodium hydroxide to make 3 pounds of soap were added to a modified ribbon type soap crutcher. This mixture was then heated to 177° F. whereupon there was added to it over a period of 10 minutes while being agitated 216 pounds of powdered cleanser. The addition of the powder resulted in a lowering of the bath temperature to 148° F. The over-all composition was mixed for a period of 5 minutes and then poured into a container at 146° F. A resultant analysis of the paste showed a specific gravity of 1.28 and a moisture content of 19.8%.

EXAMPLE 4

	Percent
Cleansing powder	75.5
Water	22.40
Glycerin	1.05
Soap (formed in situ)	1.05

The same steps were followed in preparing this composition as were used in Example 3 with the exception of the time in adding the powdered cleanser to the glycerin, soap and water mixture; the temperatures of the mixture at various stages and the time in mixing the over-all composition. In this example, 10 minutes were consumed in adding the powdered cleanser. The glycerin, soap and water mixture was heated to 185° F., cooled to 146° F. upon addition of the powder; and poured at 142° F. The mixing time for the over-all composition was extended to 30 minutes. The resultant analysis of the paste showed a specific gravity of 1.46 and a moisture content of 22.4%.

5
EXAMPLE 5

	Percent
Cleansing powder	72.0
Water	26.0
Glycerin	1.0
Soap (formed in situ)	1.0

The same steps were followed in preparing this composition as were used in Example 4 with the exception of the temperature of the mixture at the various stages. The glycerin, soap and water mixture was heated to 172° F.; cooled to 143° F. upon addition of the powder; and poured at 139° F. A resultant analysis of the paste showed a specific gravity of 1.47 and a moisture content of 26.0%.

EXAMPLE 6

	Percent
Cleansing powder	76.54
Water	21.40
Glycerin	1.03
Soap (formed in situ)	1.03

The same steps were followed in preparing this composition as were used in Example 4, with the exception of the temperatures of the mixture at various stages and the time in mixing the over-all composition. The glycerin, soap and water mixture was heated to 173° F., cooled to 142° F. upon addition of the powder, and poured at 140° F. Mixing time for the over-all composition was extended to 40 minutes. The resultant analysis of the paste showed a specific gravity of 1.45 and a moisture content of 21.4%.

EXAMPLE 7

	Percent
Water	24.295
Dye	0.01
Glycerin	1.000
NaOH (38% aqueous solution as Na ₂ O)	0.270
Hydrogenated tallow fatty acids	0.925
Cleansing powder	Balance

The cleansing powder of this example comprises the following ingredients:

	Percent
Silex	85.4
Sodium tripolyphosphate	3.99
Commercial detergent mixture	10.57
Perfume	0.04

The commercial detergent mixture referred to above comprises as the principal ingredients the following:

	Percent
Sodium dodecyl benzene sulfonate	35
Sodium tripolyphosphate and decomposition products thereof	40
Sodium silicate	7
Sodium sulfate	Balance

It also contains fractional percentages of sodium carboxymethyl-cellulose, tarnish inhibitor, preservative and fluorescent dye.

The paste cleanser of this example was compounded as described above.

In order to evaluate the foam properties of the product of the invention, a measured amount of the product is placed in a 500 ml. graduated cylinder with sufficient water added to bring the volume to 100 ml. A perforated piston is then placed in the cylinder and readings taken of the foam height after every five strokes of the piston through the liquid. This test is satisfactory for measuring relative differences in foaming power of different products.

The following three tables indicate the relative foaming powers of the paste cleanser of this invention, the cleansing powder per se, and two well known paste cleaners, A and B.

Table I indicates the relative foaming power in milli-

liters of the cleansing powder per se and the paste scouring cleanser of this invention when 5 to 30 piston strokes are applied to a 500 ml. graduated cylinder containing 33 grams of one of the materials to which has been added sufficient Jersey City tap water at 120° F. to bring the volume up to 100 ml.

6
Table I

	Number of Piston Strokes	Height of Powder Solution in ml.	Height of Paste Solution in ml.
5		234	220
10		323	330
15		390	434
20		465	500
25		493	
30		500	

The foaming power of the paste compared favorably with that of the cleansing powder alone as can be seen from Table I.

Table II indicates the relative foaming power in milliliters of the paste cleanser of this invention and two well-known paste cleansers, A and B, when 5 to 60 piston strokes are applied to a 500 ml. graduated cylinder containing 45.8 grams of one of the materials to which has been added sufficient water at 150 p.p.m. hardness at 120° F. to bring the volume up to 100 ml.

Table II

	Number of Piston Strokes	Height of Cleanser Solution A in ml.	Height of Cleanser Solution B in ml.	Height of Paste Solution in ml.
35				
5		174	150	275
10		225	250	374
15		250	300	460
20		300	350	500
25		299	364	
30		310	424	
35		325	450	
40		324	469	
45		336	470	
50		349	470	
55		350	471	
60		350		

Table III indicates the relative foaming power in milliliters of the paste cleanser of this invention and the two well-known cleansers, A and B, when 5 to 60 piston strokes are applied to a 500 ml. graduated cylinder containing 20.8 grams of one of the materials to which has been added sufficient water at 300 p.p.m. hardness at 120° F. to bring the volume up to 100 ml.

Table III

	Number of Piston Strokes	Height of Cleanser Solution A in ml.	Height of Cleanser Solution B in ml.	Height of Paste Solution in ml.
55				
5		206	200	225
10		300	224	325
15		324	250	370
20		340	300	400
25		380	350	425
30		410	400	450
35		418	425	500
40		420	440	
45		429	450	
50		448	470	
55		459	500	
60		460		

The foaming power of the paste cleanser of this invention proved to be far superior to that of the paste cleaners A and B.

To determine the detergency power of the product a ceramic tile plate was coated with a mixture of Oildag, linseed oil, Crisco and Skelly Solve C, and heat treated at 135° C. for a period of from 23 to 25 minutes. The tile was then washed with a sponge containing the prod-

uct, operated by a mechanical windshield wiper device. The number of strokes necessary to completely remove the soil with the given product was measured. The paste product was found to be superior to the cleansing powder taken alone.

The following Table IV indicates the relative detergency power of the cleansing powder per se and the paste cleanser of this invention as determined by the above procedure.

Table IV

Test No.	Cleansing Powder	Paste Cleanser of the present invention
1.....	141	117
2.....	135	121
Average.....	138	119

As will be apparent the smaller the number of strokes required the better the cleansing ability.

In a test made to determine the comparative lime soap dispersion properties of the paste cleanser of this invention and paste cleansers now on the market, ceramic tiles were washed with the product to be tested in 300 p.p.m. hard water. The plates were then rinsed twice with 300 p.p.m. hardness water and stained with methyl violet. The methyl violet sticks to any lime soap present and is therefore easily seen. From this test it was apparent that no lime soap remained on the ceramic tile surface when the paste cleanser of the present invention was used although from $\frac{1}{4}$ to $\frac{1}{2}$ of the total area of the tile was stained when the tile was washed with other commercially available paste cleansers.

In the above examples the cleansing powder is stated to consist of silex, dodecyl benzene sulfonate, and sodium tripolyphosphate. It should be understood, however, that in the cleansing powder (and hence in the resulting paste type scouring cleanser of the present invention) the sodium tripolyphosphate can be replaced by other alkali metal phosphates such as tetrasodium pyrophosphate, sodium acid phosphate, potassium tripolyphosphate or the like.

While the non-soap anionic synthetic detergent of the cleansing powder is preferably dodecyl benzene sulfonate, it should also be understood that it is within the purview

of this invention to use other alkyl aryl sulfonates having an alkyl chain of from 8 to 18 carbon atoms, other non-soap anionic synthetic detergents such as coconut oil fatty acid monoglyceride alkali metal sulfates, fatty alcohol sulfates or sulfonates or mixtures of detergents such as nonionics and alkyl aryl sulfonates.

In the above examples the lubricant has been defined as glycerin; however, it is within the purview of this invention to use other polyhydric alcohols or their ethers such as glycol, glycol ether, sorbitol or the like.

Summarizing, the present invention is based upon the discovery of a new composition which comprises a cleansing powder comprising silex, a non-soap anionic synthetic detergent, and an alkali metal tripolyphosphate combined with a high titer soap, a polyhydric alcohol or ether thereof, and water to form a highly efficient paste type scouring cleanser.

While the invention has been described in terms of preferred embodiments thereof, it is to be understood that considerable variations from the details disclosed might be made without departing from the true scope and spirit of the invention. Accordingly, the invention is to be limited only by the claim set forth hereinafter.

What is claimed is:

- 25 A paste scouring cleanser consisting essentially of about 50% to 73% of silex, about 2% to 10% of an alkyl benzene sulfonate having an alkyl chain of from 8 to 18 carbon atoms, about 4% to 10% of sodium tripolyphosphate, about 0.6% to 2.5% of a high titer soap having 30 a titer of about 25° to 60° C., about 1% to 3% of glycerin, and about 15% to 30% of water, the foregoing percentages being by weight.
